UNITED STATES PATENT OFFICE.

ALEXANDER GRAHAM CLARK, OF WIMBLETON PARK, ENGLAND.

VALVE FOR INTERNAL-COMBUSTION ENGINES.

1,112,523.

Specification of Letters Patent.

Patented Oct. 6, 1914.

Application filed November 7, 1912. Serial No. 739,101.

To all whom it may concern:

Be it known that I, ALEXANDER GRAHAM CLARK, a subject of the King of Great Britain, residing at 153 Melrose avenue, Wimbleton Park, in the county of Surrey, England, have invented certain new and useful Improvements in or Relating to Valves for Internal-Combustion Engines, of which the following is a specification.

This invention relates to rotary distributing valves for internal combustion engines of the kind in which the speed of rotation is less than one half of the crank shaft speed and in which the external inlet and exhaust ports are arranged side by side in the valve casing or seat and the internal inlet and exhaust ports which communicate with the working cylinders are arranged diametrically opposite each other in the valve casing. In engines of this kind having their inlet and exhaust ports arranged as above stated, the length of the internal inlet and exhaust ports communicating with the working cylinders is of necessity limited by the internal diameter of the cylinders and the width is dependent upon the diameter of the valve casing. The ports leading to the external inlet and exhaust passages are however only restricted as regards their length by the distance existing between the longitudinal axes of the working cylinders while their width is dependent upon the diameter of the valve and its casing which it is desirable to keep as small as possible. Therefore in order to obtain the necessary area of the ports leading to the external inlet and exhaust passages I make them considerably longer than the internal diameter of the working cylinders, that is to say they may be as long as the ports in the valve casing. Since however the length of the valve ports is then greater than the length of the internal inlet and exhaust ports, only a portion of the valve ports can register with the external inlet and exhaust ports. It is therefore necessary in order to obtain satisfactory working of the engine, that this restriction in effective port area shall be avoided and it is the chief object of my invention to provide means for accomplishing that result.

According to this invention the valve body is provided with a plurality of radial passages which communicate with each other in the body of the valve and which are so disposed that when one of the said passages reg-

isters with the external inlet or exhaust port a sufficient number of the other passages will register with the working cylinder to insure that the total effective area of the valve ports registering with the passages leading to the working cylinder shall be equal to or not less than the area of the valve port registering with the port or passage communicating with the external inlet or exhaust pipe. The disposition of the aforesaid radial passages in the valve body is such that as the said body rotates in its casing or seat, the said passages place the external exhaust or inlet ports into communication with the working cylinder according as the engine is performing the exhaust or the suction stroke, while during the compression and working strokes the said external exhaust or inlet ports are covered and therefore kept closed by the walls of the valve casing or seat. The ports in the valve casing or seat, leading to the working cylinder are diametrically arranged as aforesaid and are of the same area so that two equal and opposite surfaces of the cylindrical valve body are exposed simultaneously to the explosive force, whereby the resulting pressures on the said valve body are balanced as is well understood. By arranging these ports so that their axis is more or less displaced from coincidence with the diameter of the valve body, I can provide for a certain degree of preponderating pressure acting in a direction to keep the valve body firmly pressed toward the inlet and exhaust ports in the valve casing when the explosions occur, thus preventing any leakage from taking place owing to wear of the valve and its casing or seat.

In order that the said invention may be clearly understood and readily carried into effect the same will now be described more fully with reference to the accompanying drawings in which:

Figure 1 is a sectional elevation of a four cylinder vertical engine provided with one form of the improved rotary valve. Fig. 2 is a transverse section taken on the line 1—1 of Fig. 1. Fig. 3 is a transverse section showing a modified arrangement of the valve illustrated in Figs. 1 and 2. Figs. 4 to 6 are transverse sections similar to Fig. 3 showing modifications of the valve. Fig. 7 is a vertical section through the valve chamber of a two cylinder engine with the valve removed to show the disposition of

the ports communicating with the working cylinders and the external inlet and exhaust pipes.

Like letters of reference indicate similar parts in all the figures.

A A are the cylinders provided with passages A^{2x} for the reception of spark plugs or fuel injection valves and A^x A^x are the water jackets surrounding the cylinders.

10 A° is the cavity or casing forming the valve seat for the cylindrical rotary valve B.

Referring first more particularly to Figs. 1, 2 and 3, the rotary valve B is disposed transversely with respect to the axes of the

15 working cylinders, and is in one piece mounted in the valve seat A° which in Figs. 1 and 2 extends horizontally above the combustion chambers of the various cylinders and in Fig. 3 extends horizontally along

20 one side of the said cylinders. The said valve body is provided with four sets of ports, one set for each cylinder, each set comprising in the particular examples now being described, four passages b' b² b³ b⁴

25 which extend transversely through the valve body. a' a² and a³ a⁴ are the two pairs of peripheral ports in the valve casing; the ports a' a² being the internal ports communicating with the working cylinder and

30 the ports a³ a⁴ being the ports communicating with the exterior inlet and exhaust passages. b' b² b³ b⁴ are the passages in the valve body which coöperate with the ports a' a² a³ a⁴. The sets of ports in the

35 valve body are placed at different angular positions relatively to each other so as to provide for the correct timing of the inlet and exhaust of the different cylinders. The ports a' a² are diametrically arranged with

40 respect to each other and communicate with the working cylinders through passages a'' and a^{2x}, the said ports being adapted to expose equal areas of the valve on each side, so that when the explosion takes place in

45 the cylinder at each firing stroke, the resulting forces acting upon the valve are balanced as is well understood. The ports a³ and a⁴ lie side by side in a position more or less at right angles to the plane passing

50 through the ports a' and a². In Figs. 1 and 2 the said passages a'', a^{2x} communicate separately with the cylinder but in Fig. 3 they communicate with the cylinder through a single opening a° which is common to the

55 two passages. The ports a³ a⁴ communicate with the inlet and exhaust pipes A³ A⁴ through the passages a^{3x} a^{4x}. b⁵ b⁶ are longitudinal passages or cavities in the valve body for the circulation of the cool-

60 ing water or it may be air which may be caused to flow through these spaces by a fan or by the suction of the engine, and on leaving the valve in a heated condition

65 may be advantageously passed through the carbureter to assist in vaporizing the fuel.

When water is used stuffing boxes such as b⁶ b⁶ are provided at the extremities of the valve seat to receive the ends of the pipe b⁷ forming part of the cylinder cooling circuit. Packing rings b¹⁰ may be provided on the body of the valve at intervals between the various cylinders to insure a gas tight fit for the valve in its casing or seat. Continuous rotary motion is in the example shown imparted to the valve body by a worm wheel b⁸ keyed to one end thereof and meshing with a worm mounted on a shaft b⁹ which is driven from the crank shaft of the engine through appropriate gearing.

In the position in which the valve and the piston are represented in Figs. 2 and 3, the piston is about to perform its downward working stroke and the valve has completely closed the pair of ports a' and a² 35 communicating with the cylinder and also the pair of ports a³ and a⁴ communicating with the inlet and exhaust pipes. The valve is intended to revolve in a clockwise direction as shown by the arrow. When the piston reaches the extremity of its working stroke or thereabout, the valve will have moved through an angular distance sufficient to bring the passage b⁴ therein into communication with the exhaust port a⁴ 95 and the passages b' and b³ into communication with the cylinder ports a² and a', the passage b² remaining closed; the piston is thus able to expel the exhaust gases through the cylinder ports a' a² and the exhaust port a⁴ 100 a⁴, as it performs its upward or scavenging stroke. At the next downward or suction stroke of the piston, the valve will bring the passage b⁴ opposite the inlet port a³ while the passages b' and b³ still remain 105 in communication with the cylinder ports a² and a', and the passage b² still remains closed; the explosive charge is thus able to enter the cylinder from the inlet port a³ through the cylinder ports a' a². When 110 the piston reaches the end of its suction stroke or thereabout the valve will have brought all the passages in the valve body into a position in which they are closed by the valve seat, so that on the return stroke 115 of the piston, the charge within the cylinder will be compressed and firing will take place in order to effect another working stroke of the piston. From this point the cycle of operations is repeated, the valve body 120 moving through an angle of 90° during each cycle and revolving at a speed which is one eighth that of the engine crank shaft. In the foregoing description I have explained the action of the valve in connection with 125 only one of the cylinders; it will of course be understood that a similar cycle of operations takes place in connection with each of the other cylinders, the relative angular position of the various sets of ports in the 130

valve body being so chosen as to obtain a correct sequence of operations in the various cylinders.

Instead of arranging the valve and its seat to extend transversely with relation to the axis of the cylinders as above described, so that one valve serves to control all the cylinders, I may provide each cylinder with a separate valve, in which case 10 the said valve may be arranged with its axis vertical and be disposed either at the side of or above the cylinder. Obviously when the valve body is made of the elongated form shown in Fig. 1, it need not of 15 necessity be made from a single piece of metal but may be made in several lengths (each embodying a set of the ports) joined together by screwing or otherwise. Such a form of the valve body would also provide for a certain amount of angular adjustment 20 to each other and thus enable the various sets of ports to be readily adjusted to their proper relative angular positions if necessary. 25

In describing the working of the valve in connection with the preceding figures, I have assumed that each set of the ports in the valve body is four in number, which 30 will generally be found the most advantageous. I do not desire however, to limit myself to that number which may be increased as required provided the ports are always arranged equidistantly and in the same or 35 approximately the same transverse plane. Neither do I desire to limit myself to the specific arrangements of the said passages above described. For example the four ports and passages may be arranged as 40 shown by Fig. 4, in which case the central cooling space shown in the valve body in the preceding figures would be absent, otherwise however the valve would operate in an 45 analogous manner to that already described.

With a valve having four or more ports, the inlet and exhaust passages a^3 and a^4 may if desired be arranged at a greater distance apart than is shown in the preceding figures, thereby obtaining a larger bearing surface or 50 valve seat for the valve between the said ports. Such an arrangement is illustrated by Fig. 5. The valve as in the previous cases revolves at one eighth of the engine shaft speed; in the position in which the said valve is shown the inlet and exhaust ports in the valve seat are closed, the piston being in the act of performing its downward working stroke. On the completion of this stroke and during the return or scavenging stroke 55 the valve will move into a position to bring the passage b^3 opposite the exhaust port a^3 and the passages b^1 b^2 opposite the cylinder ports a^2 a^1 , the other passage b^2 remaining closed. As the piston completes its 60 scavenging stroke, the valve moves into a

position to bring its passage b^3 opposite the inlet port a^4 and its passages b^2 b^4 opposite the cylinder ports a^1 a^2 , the port b' remaining closed, so that the explosive mixture enters the cylinder through the ports a^3 a' and a^2 . On the commencement of the compression stroke, the valve will have moved into a position wherein all its ports are closed, during the working stroke. The valve will continue to operate in the manner above described during each cycle of operations of the engine. 70 75

Fig. 6 is an example in which the valve has only three ports and passages b' b^2 b^3 arranged radially; its speed of revolution is one sixth instead of one eighth that of the crank shaft. In the position in which the valve is shown the inlet and exhaust ports in the valve seat are closed and the piston is supposed to be in the act of performing its downward working stroke. On the completion of the piston's working stroke and during its return or scavenging stroke, the valve will move into a position to bring the passage b' opposite the exhaust port a^4 and the 80 passage b^2 opposite the cylinder port a^2 , the other passage b^3 remaining closed. As the piston completes its scavenging stroke, the valve moves into a position to bring its passage b' opposite the inlet port a^3 and its 85 passage b^3 opposite the cylinder port a' , the other passage b^2 being closed, so that a charge of explosive mixture is drawn into the cylinder during the ensuing suction stroke of the piston. On the commencement 90 of the next stroke of the piston *i. e.* the compression stroke, the valve will have moved into a position to close the inlet and exhaust ports in the valve seat and the valve will continue to operate in the manner above described during each cycle of operations of the engine. 95 100

What I claim and desire to secure by Letters Patent of the United States is:—

1. In an internal combustion engine, the 110 combination with a cylindrical valve body having a plurality of intercommunicating passages extending transversely through it with their ports arranged equi-distantly and all lying in the same or approximately the 115 same transverse plane, of a cylindrical valve casing or seat having a pair of peripheral inlet and exhaust ports adapted to co-operate with the ports in the valve body and also having a pair of peripheral ports communicating directly with one and the same end of the working cylinder, and being of such area that when one of the valve ports registers with the external inlet or exhaust port a plurality of the other valve ports will register with the ports leading to the working cylinder. 120 125

2. In an internal combustion engine the 130 combination with a cylindrical valve body having two intercommunicating passages ex-

tending transversely through it with their four ports arranged equidistantly and all lying in the same transverse plane, of a cylindrical valve casing or seat having two pairs of peripheral ports one pair being arranged side by side and communicating respectively with the inlet and exhaust pipes or conduits and the other pair arranged diametrically or approximately diametrically opposite each other and communicating with passages extending from one and the same

end of the working cylinder and means for imparting continuous rotary motion to said valve body from the engine shaft at one eighth of the speed of the latter. 15

In testimony whereof I affix my signature in presence of two witnesses.

ALEXANDER GRAHAM CLARK.
